UNITED STATES PATENT OFFICE

JOHN BERGSTEN, OF HERMOSA BEACH, CALIFORNIA

ELEVATOR

Application filed February 4, 1924. Serial No. 690,347.

This invention relates to elevators or other lifting devices, such as may be used for well casing or the like, and which elevator includes the usual body member having a gate with positive means for effecting a locking relation between the body and the gate so that any work embraced by the body and gate cannot slip from the elevator.

An object of the present invention is to provide an elevator with positive locking means which cannot be accidentally disturbed or unlatched or unlocked, due to jarring or a disturbance of the parts carried by the elevator, but which can only be unlocked by an operator intentionally operating the latching means.

With the above and other objects in view the invention contemplates an improved elevator which is so formed and constructed as to provide a resistance to stress and strain and which positively ensures a locked relation of the various parts when the same is embracing work.

In the drawing:

25 Figure 1 is a fragmentary side elevation, certain parts being in section, of the improved elevator;

30 Figure 2 is a plan view, partly in section, on the line 2—2 of Figure 1, and illustrating the improved locking means associated with the elevator;

35 Figure 3 is a fragmentary enlarged view partly in section and taken on the line 3—3 of Figure 2;

40 Figure 4 is a fragmentary view partly in section and on the line 4—4 of Figure 5, and in the plane of Figure 1 illustrating the cooperating parts of the body and the jaw or gate and the latching means; and,

45 Figure 5 is a fragmentary enlarged view of the locking means shown in Figure 2.

Corresponding parts in all the figures are designated by the same reference characters.

50 Referring with particularity to the drawing, the improved elevator as a whole is designated by A, of which a is the body and b the gate. In the present elevator the body member a is provided with diametrically disposed extensions designated generally by c, which extensions are formed so that a bail d

may be associated therewith. The so-called extensions c in the present showing comprise two spaced members 1 and 2 for each side of the elevator body. The members 1 are adapted to cooperate with the bail d which comprises two members 3 and 4. The load or weight of the elevator plus any article or device carried by the elevator is supported by the bail plus a suitable tackle associated with the bail. To ensure that the bail does not become disconnected from the elevator body I provide the means e which comprises stirrup-like members pivoted to the extensions 2 and provided with releasable catches 5 adapted to engage with the extensions 1. The portions 6 of such stirrup-like members are bored as shown at 7 so as to confine a spring-actuated catch or bolt 8 to which is joined a finger-piece or head 9, and each extension is recessed as shown at 10 to confine a portion of the bolt 8 when the stirrup-like member is revolved so as to straddle the space between the members 1 and 2. It is thus seen that the bail is positively retained upon the extensions 1.

The body may be curved as shown at 20 and the gate is correspondingly curved as shown at 21 so that the normal space between the body and the gate is circular. The gate may be hinged to the body as shown at 22. To this end the body is provided with a series of spaced knuckles 23, 24 and 25, between which knuckles 26 and 27 of the gate are placed, and the usual pin 28 passed through aligned bores in such knuckles of the gate and body.

One of the main features of this elevator resides in the positive latching means designated by f for ensuring a proper closing of the gate to the body. Said latching means includes a lever 40 and a bolt 41. In the embodiment shown the bolt is carried by the gate being received in a bore 42 of such gate b. The body a is formed with an extension 43 which is provided with a bore 44 adapted to align with the bore 42 when the gate is closed to the body, as illustrated in full lines at Figure 2. The gate b is constructed to totally confine the lever 40 for actuating the bolt 41 when the gate and the body are closed so as to embrace some object, and this con-

struction ensures that the lever 40 will not be disturbed by extraneous objects hitting the gate and swinging the lever 40 to unlatch the gate from the body. This desired result is accomplished in the present invention by enlarging the head of the gate as shown at 45, and so that a portion of such head is formed with two spaced flanges 46 and 47. At this point it is obvious that in place of providing flanges I might provide the equivalent by recessing the enlarged head, which of course would form flanges. These flanges extend a distance sufficiently outwardly from the outer surface of the gate to totally receive therebetween the lever 40 when the gate and body are in closed relation. The gate and body are likewise formed to have a stress-resisting relation when locked together, and this stress-resisting relation is accomplished by recessing the body to provide a mortised seat as shown at 100 so that a tenon projection or extension 48 on the end of the gate *a* may be received within such recessed portion as illustrated in Figures 2, 4 and 5. It will be noted that the recess 100 forms two shouldered portions in the body, as shown at 49 and 50, and the shouldered portions cooperate with the extension 48 and further that both of such shouldered portions are curved to conform to the inner curvature 20 of the body. The extension 48 extends at right angles to the parts *c* in the showing and such extension would have its wall portion 51 cooperate with the portion 52 of the gate. Thus any strain imposed upon the gate would tend to force the portion 52 of such gate against the wall 51, but this movement would in a measure be resisted by the part 48 contacting with the wall surrounding the recess 100 in the body. Likewise movement in an inward direction would be resisted by the extension 48 contacting with the flanges 49 and 50 of the body.

Of course the latching means *f* could be of any form other than that shown in the drawing, the main point being to so confine the latching means, and particularly the member for actuating the latching means, as to prevent such latching means from being accidentally opened, due to the elevator striking extraneous objects. The present latching means, and particularly the handle member thereof, is so formed that an operator would have to intentionally operate the same in order to unlatch the gate from the body. The bolt 41 may be transversely recessed, as shown at 60 for reception of a head portion 61 of the lever or arm 40, and preferably the head 61 extends partially within the recess 60 so as to allow play of the head within such recess. The lever is pivoted as shown at 62 between the flanged portions of the gate, and an end of such lever is provided with a T handle 63. Thus, an operator may reach between the flanges 46 and 47, and the

fingers may close upon the T handle 63 and by swinging the lever outwardly, as shown in Figure 5, retract the bolt 41 within the bore of the gate and a further pull upon the lever will allow the gate to swing open from the body. I provide a coil spring 64 between an end of the bolt 41 and the gate so as to at all times normally tend to force the bolt outwardly from the bore 42 in the gate, and said bolt is likewise provided with a bevel nose portion 65 so that a swinging of the gate inwardly will automatically retract the bolt when the nose portion contacts with a bevel portion 66 of the extension 43 to where the bolt may be passed under spring actuation within the bore 44 of the extension 43 to lock the gate to the body. As shown in Figure 3 I may provide two of such springs 64, spaced apart, to force the bolt into locking engagement with the body.

It will thus be seen that in the present invention I have provided positive locking means for holding the bail to the body, as well as providing a stress-resisting formation between the body and the gate with a latching mechanism which cannot be disturbed except intentionally by an operator.

It is obvious that various changes and modifications may be made in practicing the invention, in departure from the particular showing, without departing from the true spirit of the invention.

Having thus disclosed my invention, I claim and desire to secure by Letters Patent:

1. A casing elevator comprising a body element, a gate element hinged to said body element for movement between open and closed positions with respect thereto, a lug on one of said elements, the other of said elements having a recess to receive and completely surround said lug when said gate element is closed whereby said gate element is held against movement relative to the body element in all directions transversely of said lug, and means to hold said gate element closed.

2. A casing elevator comprising a body element, a gate element hinged to said body element for movement between open and closed positions with respect thereto, lug and recess formations on said elements, respectively, cooperating to hold said elements against movement relative to one another in all directions transversely of said formations when said gate element is in closed position, and latch means entirely independent of said formations to hold said gate element in closed position.

3. A casing elevator comprising a body element, a gate hinged to said body element for movement between open and closed positions with respect thereto, lug and recess formations on said element, respectively, cooperating to hold said elements against movement relative to one another in all directions trans-

versely of said formations when said gate element is in closed position, an outwardly directed extension on said body element adjacent to the aforesaid formation thereof, said extension having a lock bolt receiving opening therein, a lock bolt slidably mounted in said gate element outwardly of the aforesaid formation thereof for engagement in the opening in said extension, and actuating means for said lock bolt.

4. A casing elevator comprising a body element, a gate hinged to said body element for movement between open and closed positions with respect thereto, lug and recess formations on said element, respectively, cooperating to hold said elements against movement relative to one another in all directions transversely of said formations when said gate element is in closed position, an outwardly directed extension on said body element adjacent to the aforesaid formation thereof, said extension having a lock bolt receiving opening therein, a lock bolt slidably mounted in said gate element outwardly of the aforesaid formation thereof for engagement in the opening in said extension, spring means for projecting said bolt into the opening in said extension when the gate is closed, and a pivoted lever operatively connected with said bolt for withdrawing same from said opening.

In testimony whereof, I have signed my name to this specification.

JOHN BERGSTEN.
